UNITED STATES PATENT OFFICE.

KARL DUSCHANEK, OF FREIBURG, GERMANY.

CALCULATING-MACHINE.

SPECIFICATION forming part of Letters Patent No. 334,419, dated January 19, 1886.

Application filed October 8, 1883. Serial No. 108,451. (Model.) Patented in England August 4, 1883, No. 3,828.

To all whom it may concern:

Be it known that I, KARL DUSCHANEK, of Freiburg, in the Empire of Germany, have invented new and useful Improvements in 5 Calculating-Machines, (for which I have applied for provisional protection in Great Britain on the 4th day of August, 1883, No. 3,828), of which the following is a specification, reference being had to the accompanying drawings.

This invention relates to apparatus for mechanically performing arithmetical calculations, and can be used for adding, subtracting, and multiplying figures of any desired 15 magnitude with the greatest ease and facility and in the most accurate manner.

The invention consists in the construction and combination of devices hereinafter more fully described, and then set forth in the 20 claims.

In the drawings, Figure 1 is a side elevation of a machine constructed according to my invention. Fig. 2 is a plan view of the same. Fig. 3 is a side elevation of the movable portion of the machine from the side facing the stationary part of the machine. Fig. 4 is a horizontal section of the machine with parts of the mechanism removed. Fig. 5 is an elevation or end view, partly in section, looking 3c toward the right of Fig. 2. Fig. 6 is another horizontal section with parts of the mechanism removed. Fig. 7 is a detail view of part of the mechanism. Fig. 8 shows two portions of mechanism for arresting some of the numbered disks. Fig. 9 is a plan and elevation of mechanism which may be used in lieu of toothed wheels. Figs. 10, 10^a, and 11, and 11^a show in plan and elevation different positions of the device for holding the drums in a raised 40 position. Fig. 12 shows the position of the parts when the movable portion of the machine is shifted from the position seen more fully in Fig. 6. Fig. 13 is a detail view of the toothed section and intermeshing spur-wheel 45 and lifting-rack. Fig. 13^a is a section of Fig. 13, showing also the relative arrangement of some of the number-wheels. Fig. 14 is a detail view showing a stem of a number-wheel visible through an opening in the top plate of 50 the machine. Fig. 14^a is a detail view of the means for holding and releasing the toothed section. Fig. 15 is a face view of said toothed section.

The improved machine comprises two main parts, one of which is fixed, and carries the 55 primary set of number-wheels and the other is movable and carries the secondary set of number-wheels.

As shown in Figs. 1, 6, and 12, the plate *a* forms the base or foundation of the entire machine, and above one half of this plate is arranged a top plate, *b*, which is connected with the base-plate *a* by means of vertical columns or parts *b*¹, as is clearly seen in Fig. 1. These two plates form the bearings for the various 60 shafts of the fixed portions of the machine.

On the top plate *b* is placed a face-plate, *c*, upon which are engraved or otherwise shown marks necessary for guiding the operator in the manipulation of the machine.

In rear of the plate *c* of the fixed part of the machine is arranged a plate, *d*, lying in the same plane as said plate *c*, and mounted upon a longitudinally-movable frame or carriage constituting the movable part of the machine, 75 as will be hereinafter more fully described. This frame or carriage consists, essentially, of a bottom plate, *d*¹, and vertical parts *d*², which latter support the top plate *d*, and the entire carriage supports the shafts of the number-wheels and hand-cranks, as will be hereinafter set forth.

In referring to the Figs. 4, 5, 6, and 12, more particularly, the letters *e e* indicate vertical shafts, upon which are mounted toothed sectors *f f*, the teeth *g g* of which are so disposed on the curved face of the sector that the bottom series of teeth will present a spurred segment of nine teeth, the next series of teeth a spurred segment of eight teeth, and so on, diminishing 85 in number to the top, where only one tooth is formed, as is clearly seen in Fig. 15. These sectors *f* are movable vertically upon their shafts *e*, and are also capable of rotating with the latter by virtue of a spline-and-feather connection.

In the plates *a* and *c* are journaled vertical shafts *h h*, the upper ends of which terminate in handles or knobs *h*² for turning the same. These shafts carry bevel spur-wheels *i*, which 100 engage with the bevel spur-wheels *i*², mounted on short horizontal shafts *i*¹, journaled in arms *i*¹⁰, rising from the base-plate *a*. The shafts *i*¹ also carry toothed wheels *i*¹, which engage with vertical rack-bars *i*², having arms *i*³ extending 105 obliquely therefrom, as is seen in Fig. 4.

These arms, lying in two planes, as is shown in Fig. 1, are united into one frame by the vertical rods i^1 , and they have furcated ends i^2 , which straddle the shafts e on which the 5 sectors slide up and down at points above and below said sectors—in other words, the arms i^3 , rod i^1 , and rack-bars i^2 constitute a frame for shifting the sector when said frame is moved, by turning the shaft h and the intermediate gearing. The arms i^3 of the sector-shifting frame are also guided in their up and down movements by the vertical guide-rods m' , which are secured to the top and bottom plates of the frame, a shaft, m^5 , replacing one 15 of these rods in the right-hand sector-shifting frame.

Each of the shafts h employed for shifting the sectors carries a ratchet-wheel, k , of ten teeth, into which meshes a horizontal pawl or 20 detent-lever, k^3 , mounted upon a vertical shaft, k' , and acted upon by a spring, k^2 , upon the base-plate of the machine, which holds the pawl-lever in contact with the ratchet-wheel and locks the latter. The object of 25 these contrivances is to hold the sectors in an elevated position until such time as the pawl-and-ratchet mechanism is disengaged.

Upon the shafts h are mounted disks l , as is seen in Figs. 1, 2, and 14, each of which has 30 marked upon it the nine digits and the cipher. These disks or wheels l may be termed "causation" disks or wheels since they are the initial devices concerned in the performance of all kinds of arithmetical operations—viz., additions, subtractions, multiplications, and divisions.

In the plates b and c , which lie close together, apertures l' are formed, of such size as to show only one figure at a time upon each of said 40 causation-disks. The said apertures are situated between the shafts e of the sectors f .

The figures which appear through the above-mentioned apertures are varied according to the position in which the toothed sectors have 45 been set—that is to say, the said numbers indicate how many teeth of the sectors f are in position to gear with wheels o' on the movable portion of the machine for a purpose hereinafter described.

50 In Fig. 13^a is shown, by way of example, the position of the toothed sector (shown in section) when the fourth row of teeth from the top have engaged with the wheel o' , and the numeral 4 on the disk l of the shaft h is supposed to be visible through the aperture in the top plates b c , the other numerals being concealed beneath said plates.

The mechanism hereinbefore described 55 serves to arrange the multiplicand or divisor, and hence there are provided as many sectors f and number-disks l as there are figures required in the said multiplicand or divisor.

The apparatus shown in the drawings is arranged for two figures only.

65 In order to bring the sectors to their normal positions and return the disks l to the zero-point after a calculation has been made, de-

vices shown in Figs. 1 to 6, inclusive, are employed. They consist of a shaft, m^5 , stepped in the top and bottom plates, a b , and 70 mounted by a crank or handle, m , and also bearing a toothed wheel, m^2 , at the bottom, which, through the medium of a train of gearing, m^2 , operates as many shafts m^4 as there are sectors f . The spur-wheels m^3 are on the 75 shafts m^4 and mesh into the wheel on shaft m^5 , so that by turning the latter, through the medium of the handle m all the shafts m^4 will be turned. Each shaft m^4 , carries a cam, m^{10} , (seen more fully in Fig. 6,) upon which cams 80 bear the end projections or hooks, k^4 , on the pawl-levers k^3 , so that when the said cams m^{10} by their rotation vibrate the pawl-levers the ratchet-wheels k are released from the said pawls, whereby the weight of the sectors f 85 sliding downward on the shafts e will, through the medium of the arms i^3 , racks i^2 , and gearing i^1 and i , rotate the shafts h and return the number-disks thereon to the zero-point, as has already been explained.

In order to prevent the sectors from falling too suddenly when the ratchets are released from the pawl-levers, the shafts m^4 carry partially toothed or mutilated wheels n , (seen in Figs. 6 and 14^a,) which, when the ratchets are 90 released, engage with the correspondingly-toothed wheels n' upon the shafts h , and thus act as a retarding medium, since it is evident that the intermeshing gear-wheels of the respective shafts will accomplish the desired result. The toothed wheel n' has a toothless space, n^6 , so disposed between two of its teeth that said space will come opposite the teeth of the toothed wheel n when the disk l is brought to the zero-point. It is evident that as soon as 105 the toothed wheels n have caused the wheels n' to move far enough for the space between their teeth to come opposite the teeth of the former the wheels n n' pass out of gear, and the disks l are placed at zero, as has already 110 been stated.

The cams m^{10} on the shafts m^4 act in such a manner that all the various parts of the machine are not compelled to move in the same time; but this arrangement is not absolutely 115 necessary. It should be observed that if the shafts m^5 and m^4 are caused to perform a whole revolution by the devices above referred to, all the pawl-levers k^3 will be released, and the sectors dropped to their normal positions, 120 and the disks set at zero.

Referring to Fig. 14^a we may assume that it shows the position of the means for holding one of the sectors elevated to such a height as to reveal the figure 4 on the numbered disk 125 through the aperture in the top plate, it being assumed that in this instance the wheel n on the cam-shaft m^4 has been rotated until the first tooth in gear with the fourth row of teeth is on the wheel n' on the shaft h , bearing the 130 numbered disk l and ratchet-disk k . After a further rotation of five teeth the wheel n , coming to the untoothed portion n^6 of the wheel n' , is thrown out of engagement with the latter,

whereupon the corresponding disks l are set at zero.

In order to prevent the crank m on the shaft m' from turning to the left, a ratchet-wheel, m^3 , is applied to one of the shafts m^4 , and a spring-pressed pawl, m^{10} , is mounted on the base-plate a , so as to engage with said ratchet-wheel, as is clearly seen in Fig. 4.

The shafts o on the shifting part of the machine bear the toothed wheels o' , as already stated, and also carry the numbered disks o^2 , which determine, in connection with the wheels r^2 , hereinafter referred to, the result of the arithmetical operation brought into existence by the causation-wheels l , and hence both said wheels or disks o^2 and r^2 may be termed the "result" wheels or disks. The shafts o are located opposite the toothed sectors f , and the toothed wheels o' are placed at such a height relatively to the sectors that when the disks o^2 are set at zero the sectors are in their lowermost positions and not in gear with the toothed wheels o' .

The plate d , constituting the top of the movable part of the machine, has as many apertures o^3 as there are numbered disks o^2 mounted on the shafts o . When the disks l , bearing either the multiplicand or divisor numbers, are rotated so that the numbers 1 2 3 show through the apertures the corresponding sectors are raised proportionately, and by a single revolution of said sectors a similar number of teeth, g , of the same are placed in gear with the toothed wheels o' , as is shown in Fig. 13^a. Thereupon, by a further rotation, the sectors cause the toothed wheels o' to rotate for a distance of four teeth, and the number four on a disk, o^2 , consequently becomes visible at an aperture, o^3 , in the top plate d of the movable part of the machine. The rotation of the sectors is effected by means of a crank, p , attached to the upper end of a shaft, p' , which is journaled in the plates a and b of the stationary portion of the machine. This shaft p' has a spur-wheel, p^2 , which actuates the train of gearing $p^3, p^4, p^5, p^6, p^7, p^8, p^9, p^{10}, p^{11}$, and p^{12} . At each revolution to the right of the crank p the number appearing in the apertures l is added to the number on the disks o^2 , appearing in the apertures o^3 , and this same number shown through the apertures l is consequently multiplied by the number of revolutions of the said crank p . When the crank is turned to the left instead of to the right, at each revolution of the same the number appearing in the apertures l is subtracted from the number appearing in the apertures o^3 . Additions and multiplications are therefore effected by revolutions of the said crank p to the right, and subtractions and divisions of revolutions of the same to the left. As soon as disk o^2 has effected a complete revolution, through the medium of the spur-wheel o' and corresponding sector, and 65 the number 9 is visible at its aperture o^3 , the following ten or hundred must be added by the mechanism shown more fully in Figs. 1,

3, 5, 7, 10, and 11, and of the following nature:

On the shaft o of the disk o^2 is fixed a pin, o^4 , which in its revolution raises a lever, o^5 , that is fulcrumed by or hung on a rod, o^{14} , fitted in brackets o^{16} , rising from the plate d' , as is seen in Figs. 5 and 7. This lever has a projection, o^{17} , on its under side, which is engaged by the pin o^4 as the shaft o is rotated, whereby the lever is raised as already stated. 75

In order to prevent the lever from falling below its horizontal position, a projection, o^{12} , is located on the lever at its fulcrum-point and 80 bears against a pin, o^{10} , as is seen in Figs. 5 and 7.

Upon some of the shafts e of the sectors f , and upon a shaft, l^6 , revolving at the same time as the said sectors, are mounted the drums o^6 , 85 each of which has two horizontal arms, o^7 and o^8 , as is seen in Fig. 6. When the shafts o and their numbered disks o^2 have accomplished a revolution, the lever o^5 and the corresponding drum, o^6 , are raised by the arm o^4 on shaft o , 90 and remain in this position until the shafts e and e^9 have accomplished their revolution. The said drum engages, by means of either of its arms, with the wheel o^9 , placed above the toothed wheel o' , and moves the same one step 95 forward, and thus causes the movement of the next disk when a preceding numbered disk has made a complete revolution.

For the purpose of holding the drum o^6 in a raised position during the revolution of the shafts e and e^9 , I provide devices. (Shown more fully in Figs. 10, 10^a, 11, and 11^a, in which is shown a lever, q' , acting directly upon the drum o^6 , and a spring for lowering said lever subsequent to the raising of the drum.) Neither 105 the lever q' nor the spring q are fixed to the frame of the machine, but are mounted upon a plate or piece, q^2 , which is secured to a rod, q^3 , that is fitted in the vertical bearing-pieces q^4 , secured to the top and bottom plates, a and b . 110 The to-and-fro movement of the plate q^2 is effected by means of eccentrics q^5 and q^6 , which are mounted on a shaft, q^{10} , stepped in the top and bottom plates of the machine, and arranged as is shown in Figs. 11 and 11^a. The shaft q^{10} 115 carries a spur-wheel, p^4 , which receives motion from the sector-operating mechanism. The eccentrics q^5 and q^6 are of different sizes, and they operate between studs or rods q^7 and q^8 , depending from the sliding plate q^2 , and in 120 order that they may alternately engage with said studs to move the plate to and fro the studs themselves are made of different lengths, as is clearly seen in Figs. 10 and 11. The pin or stud q^9 on the top of the plate q^2 strikes 125 against the projection q^{14} on the lever q' , and allows only sufficient play to the spring bearing upon said lever for depressing the latter to the position shown in Fig. 10^a below the drum, which depression allows the said lever 130 to fall and again to rise when the next ten is to be added.

For subtractions and divisions, the arrangement for the tens and hundreds disks is ex-

actly reversed, the disks being returned to zero by means of the arms o^8 .

In the above-described operation the sectors f are always in gear with the toothed wheels o' which are in front of them, and the multiplication and division of units is accomplished by the revolution of the crank p .

In order to effect multiplications with tens, the sector which is nearest the outside of the mechanism must be in gear with the second wheel o' , and the next sector must be in gear with the third wheel o' , a similar arrangement being extended to the other sectors. This connection is effected by mounting the shafts o , with their bearings and disks and devices actuated thereby, upon a part of the machine which can be moved to the right or to the left in relation to the fixed part of the machine. The construction of this movable part or carriage is specially illustrated in Figs. 3, 5, and 12.

The plates d d' , which carry the several parts of the machine, are connected by means of hangers d^2 with longitudinal rods d^3 , which slide in bearing-holes of upright plates a' fixed upon the foundation-plate a . As the position of the said carriage must be fixed for the various positions of the units and the tens so that the wheels o' shall come precisely opposite the sectors, two notches, a^2 a^3 , (seen in Figs. 4, 6, and 12,) are formed in the base-plate for the reception of a locking arm or pawl, d^4 . This pawl or arm is fixed upon a rock-shaft, d^5 , which rotates in bearings in the hangers d^2 , and has a lever-arm, d^6 , projecting therefrom and acted upon by a vertical push-rod, d^6 , which is encircled by a spiral spring, d^6 . By operating the push-rod the pawl d^4 is withdrawn from either of the notches in the foundation-plate to allow the movable carriage to be shifted, the spring at other times holding the parts in a locked position. The push-rod d^6 consists of two parts firmly attached together, the left part pressing upon the lever-arm d^6 , as is seen in Fig. 7. It is therefore only necessary in order to move the carriage toward the next ten to raise the pawl d^4 by means of the push-rod d^6 , and draw the carriage in a longitudinal direction, when the pawl after the carriage has reached the desired position will fall automatically into the notch in the base-plate opposite said pawl and lock the carriage in its new position.

It is obvious that as many notches a^2 will be required as there are numbers in the multiplier or quotient.

In order to be able to perceive at the end of a multiplication how many revolutions of the crank have been accomplished to bring the units, tens, or other numbers into position, the shafts r are arranged upon the carriage above mentioned, and upon them are mounted the toothed wheels r' , each provided with ten teeth and the disks or wheels r^2 , heretofore specified under the name of "result" wheels or disks. The upper plate, d , of the machine is provided with corresponding apertures, r^3 , to

show the numbers on the result-wheels r^2 . The shaft r^5 , which is journaled in the plate a and in a bracket rising from the latter, is provided with the pin r^6 , which is in gear with the toothed wheel r' , and will rotate by means of the gearing of all the wheels p^2 to p^{12} with the crank p . In this rotation the toothed wheel r' , in gear with the wheel mounted upon the shaft r^5 , is rotated one tooth farther. When the carriage is in its first position—that is to say, when operations are performed with the units only—the pin r^6 enters the teeth of the last wheel r' to the right. When a multiplication is effected with the tens, the carriage is brought into its second position, which causes the pin r^6 to enter the teeth of the second wheel r' , and a similar arrangement will correspond to the use of further numbers. The direction in which the shaft r^5 and the shafts of the disks r^2 rotate is the reverse of that in which the crank p revolves. The multiplication has therefore to be arranged upon the disks, and when a revolution of the crank p is effected in the right direction all the numbers are placed at zero in the apertures r^3 . For divisions, the revolution of the crank will be effected in a reverse direction, the numbers of the above-mentioned disks being thus placed at zero, and the quotient will appear as the result of the operation in the apertures r^3 . All the disks have grooves or indentations formed in their peripheries, into which indentations the spring-tongues o^9 and r^7 , (seen in Fig. 2,) fall as soon as a number appears at one of the apertures. As by the sudden turning of the crank a number may easily be passed over, the arrangement shown in Fig. 8 is resorted to in order to avoid such an occurrence. In this arrangement the spring r^7 fits into the concave indentations of the disks r^{11} , and a fork, r^8 , turning upon the stud or fulcrum r^{14} , has one of its prongs provided with a pointed projection, r^{10} , while the other prong terminates in a projection, r^9 , of the same shape as the concave indentations in the disk. At each rotation of the latter the distance of one indentation an oscillating movement is imparted to the fork, and at the moment when the rotation of the disk is to be arrested the mounted projection of the fork passes into the indentation of the disk and holds the latter stationary. The fork is easily released from the disk by exerting the proper force to turn the disk.

The disks o^2 and r^2 are set at zero as follows, viz: The shafts of the said disks o^2 and r^2 carry the wheels s' , provided with nine teeth, room being left vacant for a tenth tooth. These wheels are situated, as shown in Figs. 5, 6, and 12, immediately above the wheels o' and r' . (In Fig. 6 one tooth of the wheels o' is shown opposite the vacant spaces on the wheels s' .) Opposite the wheels s' are mounted partially-toothed wheels s^2 , which are rotated by means of a crank, s , together with the shaft s^6 , the toothed wheel mounted thereon, and the shafts s^3 , s^4 , s^5 , s^6 , s^7 , and s^8 . In order to hold the

crank s in the zero position, its shaft carries a disk-segment, s^9 , upon the flat portion of which bears a spring, s^{10} , as is seen in Fig. 2. The toothed wheels which transmit the rotation, and which are mounted upon the shafts s^6 s^3 up to s^8 , are for the sake of clearness not shown in Fig. 6. The position of their shafts, however, is indicated by the black circles. A single revolution of the crank s is sufficient to place the product and multiplier upon zero, and at the same time every disk controlled by the action of the crank s is placed at zero and thrown out of gear, which is the case when the rotation of the shafts of the wheels s^2 brings the parts of the wheels s' from which the tooth is missing opposite the wheels s^2 .

In the calculation of proportions, it is necessary that the row of figures appearing in the apertures o^3 and r^3 should not be placed at zero at the same time by a revolution of the crank s . It is therefore necessary that the toothed wheel mounted upon the shaft of the crank s should have room on its periphery for thirty-six teeth, but only have nine teeth, the remaining space being left vacant. By half a revolution of the crank s the row of figures in the apertures o^3 is placed at zero, and by another half-revolution of the said crank the row of figures in the apertures r^3 is likewise placed up to zero.

The various calculations are effected in the following manner, viz:

For addition, the number which is to be added to a number placed in the apertures o^3 is shown in the apertures l' . The crank p is then turned once round to the right, when the said number is added to that which was in the apertures o^3 .

For subtraction, the number which is to be subtracted from a number shown in the apertures o^3 is shown in the apertures l' . The crank is then turned once round to the left, and the result of the operation is shown in the apertures o^3 .

For multiplication, one of the factors is shown in the apertures l' and the other in the apertures r^3 , the carriage d d' being in its normal position. The crank p is then rotated to the right until zero appears in the aperture r^3 , whereupon the multiplication of units is accomplished. The carriage d d' is then pushed to the right until the pawl d^4 falls in the notch a^2 , the crank p being revolved to the right until the figure 0 appears in the second aperture r^3 . This operation is continued in a similar manner for greater numbers. The product is seen in the apertures o^3 .

For division, the operation is performed in an exactly reverse manner to that above described. The dividend is shown in the apertures o^3 and the divisor in the apertures l' , whereas the number in the apertures r^3 is left at zero. The carriage is then pushed to the right, and the winch-crank is rotated to the left. If the number 9 appears on the left in the apertures, it shows that the said carriage is moved too much to the right. The crank p

is then turned one revolution backward, the carriage is pushed back to its next position, and the crank is turned on again to the left until the figure 9 appears, when the crank is turned back again to the right, as before. The rest of the operation is repeated as above until zero appears in the row of apertures o^3 , or a smaller number than the division, which is in this case the rest of the division, whereas the quotient appears in the apertures r^3 .

I claim—

1. In a calculating-machine or arithmometer capable of performing the operations of addition, subtraction, multiplication, and division, the combination of a rotary shaft, a toothed sector capable of sliding upon and rotating with said shaft, and means for vertically moving, holding, and releasing said sector, with a causation-disk set by said toothed sector and a result-disk rotated or actuated by said toothed sector, substantially as described.

2. In a calculating-machine or arithmometer, the combination of a series of rotary shafts, a corresponding number of toothed sectors capable of rotating with and sliding upon said shafts, means for sliding, locking, and releasing said sectors, numbered causation-disks applied to the shafts of the toothed sectors, and result-wheels rotated or actuated by said toothed sectors, substantially as herein set forth.

3. In a calculating-machine, the combination of a sector having nine teeth of unequal length on its curved face, the rotary shaft carrying said sector, a rack-bar and arms, and pinion-shaft for raising and lowering said sector on its shaft, with a causation-wheel set by the sector and a result-wheel acted upon by the same, substantially as herein set forth.

4. In a calculating-machine, the combination of the train of gearing, the shafts of the causation-disks, the toothed sectors and their shafts, and means for vertically moving and rotating the sectors, with the result-disks operated by the sectors, substantially as herein set forth.

5. In a calculating-machine, the combination of the rotary shaft, the toothed sector fitted to turn therewith and slide thereon, and means for vertically moving the sector, with the shaft h , carrying the causation-disk l , and ratchet-wheel k , the shaft m^4 , having the cam m^{10} , and the pawl-lever k^3 , substantially as herein set forth.

6. In a calculating-machine, the combination of the ratchet-wheel m^3 , spring-pawl m^{20} , shaft m^4 , shaft m^5 , geared to said shaft m^4 , and crank m , with the toothed sector, its rotary shaft, and the causation and result disks, substantially as herein set forth.

7. In a calculating-machine, the combination of a motor-shaft, p' , having a crank-arm, p , a train of gearing, and the toothed sectors, with their rotary shafts, adapted to be moved to the right or left by said crank, substantially as herein set forth.

8. In a calculating-machine, the combina-

tion of the shafts having disks, on which the result of an arithmetical operation is shown, and wheels possessing ten teeth, with the toothed sectors arranged opposite said toothed 5 wheels and means for causing the sectors to engage with said wheels or be released therefrom, substantially as herein set forth.

9. In a calculating-machine, the combination of the drums provided with two arms, the 10 levers, and the shafts having pins, and an adjacent shaft having a toothed wheel and numbered disk, said levers acting upon the drums to raise them to such a height that one of the arms thereon engages with the toothed wheel 15 of the adjacent shaft and turns the same to show the next figure, substantially as herein set forth.

10. In a calculating-machine, the combination of the levers q' , and the springs g , acting 20 upon the same, with the movable drums o^6 , having arms $o^7 o^8$, the shafts of said drums, the causation and result wheels, and means for operating the same, substantially as herein set forth.

25 11. In a calculating-machine, the combination of the movable or sliding piece or plate q^2 , the spring-pressed levers mounted thereon, the eccentrics for giving a to and-fro movement to the sliding piece, with the toothed sec-

tors and the causation and result wheels, substantially as described. 30

12. In a calculating-machine, the horizontally-shiftable frame or carriage having numbered disks for indicating the result of arithmetical operations, and the shafts with toothed 35 wheels carrying said disks, in combination with the stationary frame and the rotating sectors, causation-disks, and operating devices mounted upon said stationary frame, substantially as herein set forth. 40

13. In a calculating-machine, the combination, with the stationary main frame having a notched base and carrying rotating sectors, causation-disks, and operating-gearing, of the carriage or shiftable frame having numbered 45 disks for indicating the result of arithmetical operations, and with detent or locking mechanism engaging with the notched base of the stationary frame, substantially as herein set forth. 50

In testimony whereof I have hereunto signed my name in the presence of two subscribing witnesses.

KARL DUSCHANEK.
